CLAIM

The ornamental design for a package for an archery set, as shown and described.

DESCRIPTION

FIG. 1 is a top plan view of the package for an archery set showing my new design;

FIG. 2 is a bottom plan view thereof;

FIG. 3 is a front elevation view thereof, and the broken lines shown within the recessed area are included for the purpose of illustrating surface features that form no part of the claimed design;

FIG. 4 is a back elevation view thereof;

FIG. 5 is a first end elevation view thereof; and,

FIG. 6 is a second end elevation view thereof.
